UNITED STATES PATENT OFFICE

ARTHUR HENRY ARNOLD WINDRAM, OF JOHANNESBURG, TRANSVAAL, SOUTH AFRICA, ASSIGNOR TO UNITED SHOE MACHINERY CORPORATION, OF PATERSON, NEW JERSEY, A CORPORATION OF NEW JERSEY

SEWING MACHINE

Application filed August 19, 1929, Serial No. 386,778, and in Great Britain July 5, 1928.

This invention is concerned with improvements in or relating to sewing machines and is particularly concerned with machines which are adapted for sewing travelling bags, suit cases or the like of leather or other suitable material. For the sake of brevity the term bag is used hereinafter as intended to include bags, suit cases, attaché cases and like articles.

10 It is customary, in the manufacture of certain types of bags, to make the body of the bag of cardboard or other suitable material and to cover the cardboard body with a covering of thin leather, leather cloth or the like. 15 When making such bags it is usual to insert a metal reinforcing frame in the mouth of the bag to strengthen the bag to wrap the covering material (that is the leather or leather cloth) over the reinforcing frame to hide it and finally to stitch the covering material to the body of the bag behind the metal frame. The said reinforcing frames are often formed of an iron or steel strip some 20 half an inch in width and about an eighth of an inch thick.

25 It is desirable, in order to form a neat edge to the mouth of such a bag and also to retain the frame securely in position in the bag near to the mouth thereof, that the covering should be drawn tightly over the frame before it is sewn to the body of the bag and for this purpose the operator of the sewing machine which is to stitch the material to the body of the bag behind the reinforcing frame usually presses the covering material 30 tightly over the frame with the tips of his fingers as he presents the bag to the sewing machine. It will be understood however that, as that particular position of the covering in which the operator happens to be pressing over the frame is advanced towards the needle, the operator has to remove his hand 35 out of the sewing locality and has therefore to release his grip on the covering material and to re-engage the work at another portion 40 farther away from the sewing locality. The pressure which was until that time exerted by the operator in holding the covering firmly over the frame is therefore relaxed 45 before the needle enters the work and the

covering consequently tends to become slack where it passes over the frame before it is sewn to the body of the bag. If it is sewn to the work in this slack condition the mouth of the bag or suit case is liable to present an 55 unfinished and undesirable appearance.

The present invention has as one of its aims to overcome the difficulty above set forth and provides an arrangement whereby when the covering material is to be sewn to 60 the body of the bag it may be kept tight over the frame at the sewing locality while it is being so secured to the body.

According to one of its several features the present invention is concerned with the provision in or for a sewing machine for the purpose described, of a clamping device operating automatically in timed relation to the operation of the sewing instrumentalities and adapted to clamp the material against 65 the bag at a region on that side of the reinforcing frame further from the mouth of the bag and to retain the margin of the covering securely against the body while it is sewn thereto.

According to another of its several features the present invention provides means, in a sewing machine for the purpose described, to engage the margin of the covering material near the sewing locality and to 70 impart to the same a tension directed inwardly away from the mouth of the bag during the sewing operation.

In order that the objects and the several features of the present invention may more 75 clearly be understood there will now be described with reference to the accompanying drawings and by way of example only an 80 illustrative arrangement in which the several features of the present invention are embodied in convenient forms.

In the drawings:—

Figure 1 is a view showing the said illustrative arrangement incorporated in a sewing machine of conventional type and looking at the front thereof;

Figure 2 is a side elevation looking from the left of Figure 1;

Figure 3 is a plan view of certain of the parts shown in Figures 1 and 2;

Figure 4 is a detail view showing, on an enlarged scale, certain of the parts illustrated in Fig. 2.

The sewing machine, of which the drawings show only certain parts, is of the well-known Puritan type. Such machine includes a straight hooked needle 4 which is vibrated vertically by a rising and falling arm 6. The needle is fixed in the arm 6 below a narrow work support 8 fixedly supported in the machine frame, so that the needle passes through a slot 10 in the work support as arm 6 rises and falls. The arm and consequently the needle also, have a lateral component of motion carrying the needle 4 lengthwise along the slot 10 while through the work to impart feeding movement to the latter in a direction indicated by the arrow in Fig. 3. After this feeding movement has been completed, the work is clamped against the work support 8 by the downward movement of a rising and falling presser-foot 12 correspondingly slotted to receive the needle, and the needle is thereafter withdrawn downwardly from the work and is returned to its initial position by reverse movement of arm 6 ready to rise and pass through the work again. The various figures of the drawings indicate the relation of the parts after the needle has risen and pierced the work and before the commencement of the feeding movement. An awl 14 above the work support is arranged to descend in timed relation to the movements of the needle and to pierce a hole in the work at that place through which the needle will pass as it rises, thereby relieving the needle of the necessity of piercing the hole itself. A looper 16 also located above the work support is given a more or less circular movement about the point of the needle as the latter reaches the top of its stroke to lay the thread within the hook of the needle in familiar manner. Thereafter, the needle as it retires downwardly pulls the thread through the work and sets the stitch. A thread cast-off 18 and a needle guide 20 co-operate with the needle to perform their respective functions, being carried by a second rising and falling arm 22, which is given a lateral swinging movement in company with the needle-carrying arm 6. All of the parts so far described are those customarily used in the well-known Puritan type of machine, and form no part of the present invention.

In accordance with the present invention in the form illustrated herein, there is provided a clamping member indicated generally by the reference character 24 having a serrated face to engage the under surface of the work, that is, the reversely folded marginal portion 26 which has been bent around the reinforcing member 28 (Fig. 2). This member is mounted between lugs 30 on the end of the arm 22, and is supported by means of a spring 32 confined between the inner end of a

recess, extending vertically upward within the member from its lower end, and the upper end of a stem 34 entered into such recess and having its lower end pivoted upon a pin 36 fixed in the arm 22. By means of the spring 32 the member 24 tends to be pressed upward at all times toward the presser-foot 12. An adjusting screw 38 threaded through one of the lugs 30 engages at its lower end with a ledge 40 extending laterally from the bottom of the member 24, to limit the extent of its upward movement. A plunger 42 fitting within a recess in the member 24 slightly forward of the pivot pin 36, is urged against the surface of arm 22 by means of an expanding spring 44 confined between its inner end and the end of the recess in which it is located, and tends to give a rearward tipping motion to the member 24 about the axis of the pin 36.

The serrated work engaging surface 46 of the member 24 is L-shaped in plan and designed to extend forward of the advanced end of presser-foot 12, exceeding the length of the work support 8, as well as across the line on which the needle will lay the stitches, so that it will engage the work over a considerable area. The adjusting screw 38 is intended to be set to bring the work engaging surface 46 approximately level with the upper face of the work support 8 just as the needle enters the work. The action of the two springs 32 and 44 previously referred to, in tipping the member 24 about the axis of pin 36, brings the head of such member against the front of the work support 8 at a point where such face is bevelled off to form an overhanging inclined surface 48, the contacting face of the head being correspondingly beveled as indicated at 49. Since the work support 8 is stationary, an upward movement of the member 24 will impart to its head or upper portion a lateral component of motion caused by the cam action of this inclined surface 48 upon the co-engaging surface 49 of the head. This lateral component of motion is directed forwardly of the machine at right angles to the direction of feed of the work through the latter by the movement of the needle and in a direction to draw the inturned marginal portion 26 of the covering more tightly about the reinforcing member 28 as the serrated face 46 engages such portion. A stop 50 on one of the lugs 30 limits the range of forward movement of the member 24.

The devices of the invention operate in the following manner:—After the presser-foot 12 has been lifted by the operator, the work is inserted in the machine to rest upon the work support 8 with the inturned marginal portion 26 drawn tightly around the reinforcing member 28 by the operator's fingers, and with the reinforcing member close to the line along which the needle is to form the stitches. The presser-foot is then lowered, and the stitch forming cycle begins with the descent

of the awl 14 and the ascent of the needle through the hole left by the awl upon its withdrawal to receive in its hook the thread placed there by the looper. As the needle enters the work, the arm 22 carrying the cast-off 18 and the needle guide 20 is also raised, carrying the adjusting screw 38 upwardly and releasing the member 24 from the restraint imposed upon it by such screw's engagement with the ledge 40, and also causing the springs 32 and 44 to urge the member 24 more strongly upward. Next the presser-foot 12 is lifted to free the work for its feeding movement effected by the sidewise swinging of the needle 4, and as the pressure of the presser-foot is relaxed the member 24 rises also, lifting the work from the work support and holding it against the raised presser-foot. During this upward movement of the member 24, the engagement of the bevelled surfaces respectively on the work support and the head of member 24 impart to such head a forward movement, laterally directed with respect to the feeding movement, which causes its serrated work engaging face 46 to impart a pull upon the inturned margin 26 tending to wrap it more tightly about the enfolded reinforcing member 28. The clamping foot 24 moves with the needle lengthwise of the seam being formed while in engagement with the work, holding the latter up off of the work support against the under side of the presser-foot. Thus, the member 24 serves materially to aid the needle in its feeding function, overcoming the friction resulting from pressing the work against the upraised presser-foot. Thereafter the presser-foot is lowered to bring the work back again onto the work support 8, and the needle and the member 24 are withdrawn downwardly from engagement with the work and returned to their initial positions ready for the formation of another stitch. During the downward movement of the needle, the stitch is set in the work just in front of the reinforcing member in the position indicated in Fig. 2. As the member 24 is withdrawn downwardly from engagement with the work, it is guided in its movement by the bevelled face of the work support, the spring 44 serving to urge the clamping foot against this face at all times.

The clamping foot, it will be understood, therefore acts to prevent slackness of the covering material where it is wrapped around the reinforcing member 28 and around the edge of the cardboard or other strengthening material 52 in the following manner:— First, it clamps the inturned margin of the covering material firmly against the main portion of the material as the work arrives at the sewing point whether the presser-foot be up to permit feeding or down to hold the work against the work support, and therefore retains in the inturned margin of the

covering material through the sewing operation the tension which the operator's fingers give it as it travels through the machine; secondly, it imparts an additional tension to the inturned margin by the lateral component of its movement, at right angles to the direction of feed, as it rises, following up the presser-foot during the sewing operation, and thus tends to pull the material of the covering past the needle at a point in advance of the latter, in a direction enfolding the reinforcing member the more snugly; thirdly, it prevents the covering material from being drawn toward the needle from the marginal portion by the act of setting the stitches and in fact causes the thread, as the stitches are set, to tighten the covering material somewhat by drawing the folded edge inwardly from the outward edge of the bag mouth where the material passes from the reinforcing frame more especially since the needle, in setting the stitches has to draw the covering down on to the body of the bag behind the shoulder formed by the inner edge of the frame.

It will be understood that, while the invention has been illustrated as embodied in a machine of the straight hooked needle type in which the needle is utilized to feed the work, the invention is not limited to use in this particular type of machine but may be embodied in hooked needle machines in which the work is fed by the awl or in other types of sewing machines.

What is claimed as the invention is:—

1. A sewing machine having, in combination, stitch-forming devices including feeding means, and means acting upon one layer of the work while the needle is through the work to move such layer laterally with respect to a second layer and to the direction of feed.

2. A sewing machine having, in combination, stitch-forming and work feeding devices including a hooked needle and an awl, one of which acts to feed the work, a work support, a presser-foot movable towards and from the work support and raised from the work support during the feed, and a work-clamping member engaging during the feed the surface of the work opposite to that engaged by the presser-foot and having a movement laterally with respect to the movement of the work feeding device in the direction of feed while in the work.

3. A sewing machine having, in combination, stitch-forming and work feeding devices including a hooked needle and an awl, one of which acts to feed the work, a work support, a presser-foot movable towards and from the work support and raised from the work support during the feed, and a work clamping member engaging during the feed the surface of the work opposite to that engaged by the presser-foot, moving with the work during the feed and also having move-

ment laterally with respect to the movement of the work feeding device in the direction of feed while in the work.

4. A sewing machine having, in combination, stitch-forming and work feeding devices including a hooked needle and an awl, one of which acts to feed the work, a work support, a presser-foot movable towards and from the work support and raised from the work support during the feed, and a work-clamping member engaging the surface of the work opposite to that engaged by the presser-foot, relatively movable with respect to the work support and in cam-engagement with a surface upon the latter in a manner imparting a lateral component of movement to the work-clamping member.

In testimony whereof I have signed my name to this specification.

ARTHUR HENRY ARNOLD WINDRAM.
